UNITED STATES PATENT OFFICE.

CLIFTON R. FINCH, OF NEW YORK, N. Y.

FURNACE-BRICK.

1,381,625.

Specification of Letters Patent. Patented June 14, 1921.

Application filed November 18, 1919. Serial No. 338,903.

To all whom it may concern:

Be it known that I, CLIFTON R. FINCH, a citizen of the United States, residing in New York, in the county of New York and State of New York, have invented certain new and useful Improvements in Furnace-Bricks, of which the following is a specification.

My invention relates to an improved brick for furnaces; especially a brick adapted to facilitate thorough combustion, eliminate waste of fuel and heat, and consequently increase the efficiency of the installation to which the furnace belongs.

An object of my invention is to provide a brick that is shaped to receive and contain for a time, inflammable gaseous products liberated by fuel in course of ignition; and not only to prevent the too rapid transit of such products through the furnace, and their escape unburnt by way of the exhaust flue, but also to bring about the total consumption of such products in order that the entire heat capacity of the fuel may be utilized.

A further object of my invention is to provide a brick which has a number of passages leading through its interior; the gaseous products above referred to entering these passages and escaping from same after burning; and in several forms of my invention, the brick also has a chamber which constitutes part of these passages and by which the oxidation of the products mentioned can advantageously be effected.

Another object of my invention is to provide a furnace brick which will serve the intended purpose, and which will nevertheless be simple in construction and capable of being manufactured at relatively low cost.

These and other objects and advantages of my invention will appear from the following description, taken with the accompanying drawings in which several embodiments of my invention are displayed. This disclosure, however, is illustrative only, and I reserve the right to make changes in what is actually shown herein, without departing from the nature and scope of my invention, to the full extent indicated by the general

meanings of the terms and variations of phrase in which the appended claims are expressed.

On the drawings:

Figure 1 is a side view of one form of brick according to my invention;

Fig. 2 is an end view of same; partly in section;

Fig. 3 is a side view of a modification;

Fig. 4 is an end view of what appears in Fig. 3; partly in section;

Fig. 5 is a side view of a further modification;

Fig. 6 is an end view thereof; partly in section;

Fig. 7 is a side view of still another modification;

Fig. 8 is an end elevation of same; partly in section; and

Fig. 9 is a side view and Fig. 10 an end view of a still further modification.

The same numerals identify the same parts throughout.

Referring first to Figs. 1 and 2, I indicate the body of my improved furnace brick by the numeral 1. This brick will be made of any suitable refractory or heat resisting material capable of enduring high temperature, and the relative dimensions of the brick will of course vary according to circumstances and conditions of use. As shown, the brick has rather wide opposite exterior lateral faces 2 and relatively narrow ends 3; and in the middle of the body it has a central longitudinally extending chamber 4 which is as long as the brick itself and opens through the opposite ends 3. To this chamber lead a number of ducts 5, each of which is in line with a similar duct 6; these ducts 5 and 6 connecting the chamber 4 with the opposite exterior lateral faces 2 and being substantially perpendicular to these faces.

Coöperating with the ducts 5 are additional ducts 7, which serve to connect the chamber 4 with the same exterior face as the ducts 5; but instead of running out to the middle of this face, they lead from the chamber 4 diagonally to the said face near the opposite edges of the same. Similar diagonally arranged ducts 8 coöperate with

the ducts 6 to connect the chamber 4 with the other exterior face of the brick. The ducts 7 and 8 may gradually contract from their outer ends inward to the chamber 4.

5 The ducts 5 and 6, 7 and 8, with the chamber 4 constitute passages through the brick; and in practice the brick will be mounted inside a furnace in such relation that inflammable products of combustion will flow 10 through the ducts 5 and 7 into the chamber 4, which serves as an ignition chamber. Suppose for example, that the furnace is built under a boiler, the fuel used being coal. In ordinary furnaces, a great quantity 15 of heat is lost and only a part of the heat capacity of the coal is actually utilized in vaporizing the water. The cause of this state of affairs is primarily the fact that burning coal, especially soft coal, emits 20 much inflammable gas, such as carbon monoxide and perhaps other gaseous or vaporous compounds, which is not completely burnt but passes from the fire-bed back through the heating chamber under the 25 boiler and out through the chimney stack. The result is a somewhat low efficiency and considerable expense. With the use of my improved brick in sufficient number, these gaseous products are prevented from prematurely 30 escaping, are entirely consumed, and the waste of heat usually incurred is avoided. The bricks may be supported in any suitable manner. For instance they may be suspended from movable carriers, not shown, 35 and moved at the proper rate of speed, in the line of flow of the gases of combustion, from the fire-bed toward the rear or outlet end of the furnace. At the fire-bed the flames heat the bricks to a red or greater 40 heat, and as the bricks move back from the fire-bed, the carbon monoxide and other gases flow through the ducts 5 and 7 into the chamber 4. Thus the brick for the time, 45 arrests such gases and prevents their too rapid passage to the exhaust flue. When the chamber 4 is full of such gases, to facilitate the complete combustion thereof so as to prevent the escape of any such gaseous products of combustion unburnt, and to 50 avoid the loss of the heat units which they contain, enough air is introduced into the chamber 4 for their oxidation and the gases are completely burnt and discharged through 55 passages 6 and 8. The air may be admitted at the proper point in the travel of the brick, by means which does not need to be described here because this invention relates solely to the brick with the chamber and the ducts leading to and from the same. 60 Another important advantage in addition to complete combustion afforded by bricks of this design is the diffusion of the heat liberated by the coal. By arresting the gases of combustion and burning same between the 65 fire-bed and the smoke flue, the temperature

is made uniform from one end of the interior heating chamber of the furnace to the other; and when such a furnace is beneath a boiler, the boiler is heated evenly from the front end to the rear of the same, instead of 70 being heated, as under usual conditions, too much at one end and too little at the other.

By the use of a brick of this construction, practically all of the heat which would ordinarily be lost is saved, for the inflammable 75 gases are retained long enough in the chamber 4 to be burned up entirely; and the brick in addition to retaining such gases and preventing the too rapid flow through the furnace to the exhaust flue, actively causes 80 full combustion and complete liberation of heat to take place within the furnace beginning at the fire-bed where the fuel is first ignited, and ending before the smoke flue 85 is reached. Only dead gases leave the furnace through the chimney.

Figs. 3 and 4 show a brick having two parallel chambers 4 with ducts 5, 6, 7, 8, arranged exactly with respect to the opposite exterior faces as shown in Figs. 1 and 2, 90 leading to and from each of such chambers.

In Figs. 5 and 6 I show a further modification wherein the brick instead of having flat or plain opposite faces 2 has opposite faces 9 that are slightly concave. The central chamber 4 opens through the opposite ends as before, but the ducts leading to and from this chamber are given the form of transverse recesses 10. These recesses are made so that their inner ends or bottoms are 100 curved and through their inner ends they communicate with the chamber 4. The inlet ducts are indicated at 10 and the exhaust or discharge ducts are indicated at 11. The chambers and ducts constitute passages as 105 before.

In Figs. 7 and 8 I show a further modification which has two chambers 4, the same as the form shown in Figs. 3 and 4; each chamber having a row of recesses 10 and 11, 110 in the opposite exterior faces of the brick, to admit gases to the chamber and discharge same therefrom. The two rows of recesses in each face are separated by a longitudinal rib 12. This brick may have additional 115 transverse passages 13 running from one rib 12, through the other, between the chambers 4.

In manufacturing my improved brick I can make the same in sections 14 and 15, cemented together at 16. For this purpose each section is provided with a semi-circular groove, running the whole length of the brick, on one face; and having the ducts 5 and 7 or 6 and 8 to connect this groove with 125 the opposite face as shown in Fig. 2. A similar proceeding is followed with regard to the brick shown in Figs. 5 and 6. To make the sections for the bricks shown in Figs. 3 and 4, and 7 and 8, two open-ended 130

grooves will be provided in one face and two sets of ducts or recesses in the other. When the sections are cemented together, they make a complete brick as illustrated.

5. It will be observed that in all the above described forms of my invention the ducts 5, 6, 7 and 8 and the transverse recesses or ducts 10, connect the central chamber 4 in each case with not only the middle of the

10 opposite lateral faces but also with the opposite lateral faces adjacent the edges thereof, and these ducts and recesses constitute passages which gradually contract inward toward the chamber 4.

15. Figs. 9 and 10 show a brick without a chamber 4, and with continuous passages 17 extending directly through the brick from one face to the other. This type of brick can be utilized when air does not have to be

20 injected into it. The gases take fire on entering the passages 17 and are burnt out when they leave these passages. The passages 17, and the ducts and recesses in the other forms likewise, may be square, round,

25 rectangular or of any other desired cross-sectional configuration; and so may the chamber 4.

Of course, the passages 13 shown in Figs. 7 and 8 act in the same manner as the passages 17 shown in Figs. 9 and 10.

The brick above described is shown as rectangular when viewed from the ends but obviously any other form or external configuration will come within the scope and spirit of my invention. In fact, I may even use a piece of square or round tiling with

35 ducts through the sides of same and with open or closed ends. In such cases, the hollow interior will correspond to the chamber 4 above-mentioned, and the openings through the sides will correspond with the ducts which communicate with this chamber; or

40 any other hollow body having a central chamber and ducts forming passages therewith; leading to and from same, may be adopted; and I desire the term brick to be understood to embrace all these various constructions.

The brick above described is also useful 50 for lining the inside of furnaces and stacks, especially the lower portions of the latter.

Having described my invention what I believe to be new and desire to secure and protect by Letters Patent of the United States is:

55 1. A brick for a furnace having a longitudinally extending chamber opening through the opposite ends of the brick, and ducts in the brick extending transversely with respect to the chamber and running from a plurality of points in the length of the chamber to the opposite lateral faces of the brick, said ducts connecting the chamber to the outside of the brick both through the middle and adjacent the opposite longitudinal edges of said faces.

60 2. A brick for a furnace having a longitudi-

nally extending chamber opening through the opposite ends of the brick, and ducts in the brick extending transversely with respect to the chamber and running from a plurality of points in the length of the chamber 70 to the opposite lateral faces of the brick, said ducts connecting the chamber to the outside of the brick both through the middle and adjacent the opposite longitudinal edges of said faces, said ducts contracting inward 75 from said faces toward said chamber.

3. A brick for a furnace having a longitudinally extending chamber opening through the opposite ends of the brick, ducts in the brick extending transversely of the chamber 80 and running from a plurality of points in the length of the chamber to the middle of the opposite lateral faces of the brick, and ducts running from a plurality of points in the length of said chamber to the opposite lateral faces of the brick adjacent the opposite edges of said faces.

4. A brick for a furnace having a longitudinally extending chamber opening through the opposite ends of the brick, ducts in the 90 brick extending transversely of the chamber and running from a plurality of points in the length of the chamber to the middle of the opposite lateral faces of the brick, and ducts running from a plurality of points in the length of said chamber to the opposite lateral faces of the brick adjacent the opposite edges of said faces, all said ducts contracting inward from said faces to said chamber.

5. A section for a furnace brick having a groove in one face opening through the opposite ends of the brick, and ducts in the brick transverse to said chamber and running from a plurality of points in the length 105 of said chamber to the opposite face of the brick, said ducts connecting the chamber to the opposite face both through the middle and adjacent the opposite edge of said face.

6. A section for a furnace brick having a 110 groove in one face opening through the opposite ends of the brick, and ducts in the brick transverse to said chamber and running from a plurality of points in the length of said chamber to the opposite face of the 115 brick, said ducts connecting the chamber to the opposite face both through the middle and adjacent the opposite edge of said face, said ducts contracting toward said chamber.

7. A section for a furnace brick having a 120 groove in one face opening through the opposite ends of the brick, ducts in the brick extending transversely of said chamber, said ducts running from a plurality of points in the length of the chamber to the middle of 125 the opposite face, and ducts running from a plurality of points in the length of said chamber to the last named face adjacent the opposite edges of same.

8. A section for a furnace brick having a 130

groove in one face opening through the opposite ends of the brick, ducts in the brick extending transversely of said chamber, said ducts running from a plurality of points in the length of the chamber to the middle of the opposite face, and ducts running from a plurality of points in the length of said

chamber to the last named face adjacent the opposite edges of same, all of said ducts contracting toward said chamber.

10

In testimony whereof, I have signed my name to this specification this 6th day of November, 1919.

CLIFTON R. FINCH
